UNITED STATES PATENT OFFICE.

LANSING ONDERDONK, OF NEW YORK, N. Y., ASSIGNEE TO UNION SPECIAL MACHINE COMPANY, OF CHICAGO, ILLINOIS, A CORPORATION OF ILLINOIS.

LOOPER MECHANISM FOR SEWING-MACHINES.

1,123,578.

Specification of Letters Patent.

Patented Jan. 5, 1915.

Application filed July 9, 1907. Serial No. 382,899.

To all whom it may concern:

Be it known that I, LANSING ONDERDONK, a citizen of the United States, residing at New York, in the county of New York, State 5 of New York, have invented certain new and useful Improvements in Looper Mechanism for Sewing-Machines, of which the following is a description, reference being had to the accompanying drawing and to the letters and figures of reference marked thereon.

My invention relates to new and useful improvements in looper mechanism for sewing machines, and has for its object to provide a looper-operating mechanism which 15 shall give to the looper a rapid movement at the rear end of its stroke and into the needle loop, with an extended dwell at the forward end of its stroke, whereby the looper thread is held spread for the entrance of the needle.

20 My invention consists in the parts and improvements hereinafter shown and described and set forth in the claims.

In the drawings which show by way of illustration one embodiment of my invention, Figure 1 is a front plan view, partly in section and with the parts broken away, showing a sewing machine with my looper-operating mechanism applied thereto; Fig. 2 is a bottom plan view of a sewing machine 25 embodying my looper mechanism, with the feeding mechanism broken away for the sake of clearness; Fig. 3 is an end view with a portion of the bed plate broken away to show the looper; Fig. 4 is a detail view in plan, showing the looper and its immediate operating mechanism, and also showing in dotted lines the looper in position back of needles; and Fig. 5 is a detail perspective 30 view of my preferred form of looper.

40 The bed plate 1 has rising therefrom an overhanging arm 2, carrying the usual needle mechanism at its forward end, comprising a needle bar 3, which is reciprocated from the main shaft 4, mounted in the overhanging arm. The looper 5 comprises an outwardly extending shank 6, and a portion which is curved substantially concentric to the axis of the shank of the looper. Said looper as shown in Fig. 4 is mounted 45 so as to oscillate close to, but outside of the needle 7.

As shown in Fig. 4, the looper in its oscillation, moves from a position slightly in

the rear of the needle in the direction of feed, to a position where the eye 8 of the 55 looper will hold the looper thread 9, running to the previous stitch, on the opposite side of the needle from the body of the looper.

In the operation of my machine, it is desired to give the looper movements so that the same will move forward quickly into the needle loop and then more slowly to the end 60 of its stroke, where an extended dwell is given while the needle rises and descends 65 again into the looper thread loop, which is held spread by the forward position of the looper. After the needle point has entered the looper thread loop, the looper is moved back quickly out of the needle loop, and forward 70 again into the new needle loop, which is thrown out.

In order to give the looper the movements above referred to, I have provided a lever 10 which is pivoted to a stud 11 rigidly 75 secured to the under side of the work support. Said lever 10 at its forward end is pivoted at 12 to a link 13, which in turn is pivoted at 14 to an arm 15 extending from the looper support 16, which carries the 80 looper 5. Said looper support 16 is mounted in a bracket 17, which is secured to the under side of the bed plate by suitable screws 18. Said bracket is provided at its forward end with spaced arms 19 and 20. The looper support is mounted in said arms and secured 85 therein, so as to oscillate, by any suitable means, and the arm 15 is attached to the looper support between the arms of the bracket 19 and 20.

90 The lever 10 is oscillated by means of the link 21, which link is pivoted at its rear end at 22, to a rock lever 23, which is pivotally mounted at 24 on a swinging arm 25, pivoted to the head of the machine at 26. Said 95 swinging arm 25 has an upwardly extending arm 27, carrying a ball stud 28, to which is secured an eccentric strap 29, which cooperates with an eccentric 30, on the main shaft 4.

The rock lever 23 is provided with a ball stud 31, which is connected to an eccentric strap 32, which in turn co-operates with an eccentric 33 mounted on the main shaft oppositely disposed relative to the eccentric 30.

100 105 As the main shaft 4 rotates the arm 25

will be raised and lowered and the rock lever 23 will be oscillated. By this arrangement of parts, I am enabled to give to my looper, very quick forward and backward movements. This mechanism for oscillating the link 21, forms no part of the present invention, as the same is shown, described and claimed in my co-pending application, Serial No. 213,516, filed June 21, 1904.

10 The operation of my machine is as follows: Starting with the parts shown in dotted lines in Fig. 4, and with the looper at the rear end of its stroke, as the main shaft rotates the looper is moved forward into the 15 needle loop, which is formed by the needle as it starts on its upward movement. Owing to the position of the pivotal points 14, 12 and 11, between the looper support, the link 13 and the lever 10, as the looper starts to 20 move forward the movement thereof will be very rapid and will gradually decrease in speed until these pivotal connections reach the line $x-x$, at which time the forward movement of the looper will cease, and the 25 movement of the pivotal point 12 to the opposite side of the line $x-x$ shown in Fig. 4, will practically give little or no movement to said looper. It will be apparent, therefore, that by my arrangement of parts, 30 an extended dwell will be given to the looper at the forward end of its stroke and that when said looper begins its backward movement, said movement will increase in speed until practically the rear end of the stroke 35 of the looper is reached. Furthermore, there will be practically no dwell at the rear end of the stroke of the looper.

As shown in Fig. 2, I have slotted the bracket 17 and the screws 18 which hold the bracket to the work support pass through 40 said slotted openings. By loosening the screws 18, the bracket may be adjusted so as to shift the position of the looper relative to the needles. This adjustment is quite im- 45 portant in this type of machine, so that the looper may be adjusted and properly located for various sizes of needles. Instead of making the bracket adjustable, I may use an eccentric bushing in the looper support, such 50 as shown for example in the patent to Hart, 597,610. By turning this bushing, the adjustment of the looper relative to the needle may be accomplished.

I have also indicated in this figure by the 55 arrow, the direction of the feed, and what is known as the line of feed which passes through the needle 7, and in the present machine transverse to the length of the work support.

60 Having thus described my invention, what I claim as new and desire to secure by Letters Patent, is:—

1. The combination with a work support, a needle, means for reciprocating said needle, a looper located beneath the work sup-

port and oscillating about a fixed axis parallel to the path of reciprocation of the needle, said looper being curved about said axis as a center, means for oscillating said looper including an oscillating lever, and a link connecting said oscillating lever to said looper, said link and lever being adapted to move into alinement when the looper is at the forward end of its stroke for giving an extended dwell thereto. 75

2. The combination with a work support, a needle, means for reciprocating the needle, of a looper oscillating about a fixed axis parallel with the path of reciprocation of the needle, said looper being curved about 80 said axis as a center and being so disposed that the eye thereof at the forward end of its stroke is at one side of the line of feed, whereby the looper thread running from the eye of the looper to the previous stitch is 85 held at the opposite side of the needle path from the body of the looper, and means for oscillating said looper including an oscillating lever, and a link adapted to move into alinement when the looper is at the forward 90 end of its stroke for giving a dwell thereto to hold the looper thread taut until the point of the needle has passed the looper thread.

3. The combination with a work support, a needle, means for reciprocating said needle, a looper located beneath the work support and oscillating about a fixed axis parallel to the path of reciprocation of the needle, said looper being curved about said axis as a center, means for oscillating said 100 looper including an oscillating lever, a link connecting said oscillating lever to said looper, said link and lever being adapted to move into alinement when the looper is at the forward end of its stroke for giving an 105 extended dwell thereto, a rock lever, a link connecting said rock lever and said oscillating lever, and means for oscillating said rock lever.

4. The combination with a work support, a needle, means for reciprocating said needle, a looper located beneath the work support and oscillating about a fixed axis parallel to the path of reciprocation of the needle, said looper being curved about said axis as a center, means for oscillating said looper including an oscillating lever, a link connecting said oscillating lever to said looper, said link and lever being adapted to move into alinement when the looper is at the forward end of its stroke for giving an 110 extended dwell thereto, a rock lever, a link connecting said rock lever and said oscillating lever, an eccentric connection with the main shaft for oscillating said rock lever, and means for moving said rock lever bodily. 115

5. The combination with a needle of a pivoted curved looper oscillating in a plane substantially at right angles to the path of the needle, means for operating said looper, 120

including a lever, a link connecting said lever to said looper, the pivotal connection between said link and said lever moving across a line connecting the axis of said lever and the pivotal connection between said link and said looper.

In testimony whereof I affix my signature, in presence of two witnesses.
